UNITED STATES PATENT OFFICE

2,429,571

PAPER HOLDER

Ralph Usenza, Brooklyn, N. Y.

Application March 1, 1946, Serial No. 651,051

5 Claims. (Cl. 242—55.2)

1

My invention relates to paper holders and more particularly comprises a novel and useful dispensing means for inserting, supporting and removing rolls of toilet paper from a toilet fixture.

The primary object of this invention is to provide a novel means facilitating the insertion in and removal of rolls of paper from a dispensing receptacle for roll material.

An additional object of the invention is the provision of a means, as set forth above, which will prevent the user from injuring the fingers or finger nails while inserting or withdrawing a roll of paper from the receptacle of the device.

A further important object of the invention is the provision of means for facilitating the removal of a full roll of paper from its receptacle, when access is desired for the purpose of cleaning the receptacle and the like.

A further object is the development of a device in accordance with each of the foregoing objects which shall be compact, simple, inexpensive and serviceable.

These and other important objects to become apparent as the following description unfolds, are attained by my invention, one embodiment of which has been set forth by way of example only, in the attached drawings, wherein;

Figure 1 is a front elevation of the invention as applied to a toilet paper dispenser;

Figure 2 is a vertical section taken substantially upon the line 2—2 of Figure 1 and looking in the direction of the arrows;

Figure 3 is a vertical sectional view of the other side of the receptacle of Figure 1;

Figure 4 is a horizontal sectional view through the receptacle of Figure 1, showing the arrangement of my invention;

Figure 5 is a side elevational detail, depicting the operation of my invention; and,

Figure 6 is a vertical sectional detail upon the line 6—6 of Figure 5 and looking in the direction of the arrows.

Reference is now made to the attached drawings, showing by way of example only, one embodiment of my invention, and wherein 10 designates a receptacle for dispensing roll paper, which in this instance may be a toilet paper holder. While the receptacle may be constructed of any desired material, I preferably form the same of ceramic, tile or aluminum to give a pleasing appearance. The receptacle, which may constitute a tile insert for a bathroom wall, is provided with side walls 12, 14 and a curved end wall merging into a top and bottom wall in the customary manner, not shown.

2

In accordance with the invention I provide parallel, horizontal, complementary grooves or slots in the side walls as indicated at 16, 18 respectively, these grooves including lower channel portions of relatively greater width and shorter length, shown at 20, 22 respectively to form channels receiving the spindles 24 of the customary arbor 26 upon which is removably disposed the cardboard core 28 of the usual toilet paper roll 30. The upper portions 32, 34 of grooves 16, 18 are of relatively narrower width and of greater length, and disposed rearwardly of grooves 20, 22 serving as receiving chambers for a U-shaped clamping member indicated generally at 36, said member being preferably constructed of resilient material as spring wire of a non-rust character, and including a bight 38 which may extend laterally through the walls 12, 14, with perpendicularly disposed parallel arms 40 and 42, disposable snugly in grooves 32, 34 respectively. The relative lengths, widths and disposition of these grooves is shown more clearly in Figures 2, 3 and 6.

The arm 42 is extended forwardly to provide a handle or finger grip 44 extending beyond the receptacle and is provided with a spring member 46, disposed for engagement with the top of the groove 34, to hold the clamp in position and to bias the arm 42 downwardly. Downwardly depending from the extremity of arm 40 is a pin 50 and similarly disposed on arm 42 is a pin 48, the pins being suitably positioned to engage over and retain the spindles 24 in the grooves 20, 22.

From the foregoing, the operation of the invention will now be apparent. The grip 44 is lifted against the pressure of spring 46, thus elevating the pins 48, 50, whereby a roll or the empty roll arbor may be withdrawn and a full roll inserted. When the grip 44 is released the spring 46 again biases the pins 48, 50 into the position shown in Figures 2 and 3, locking the roll in dispensing position.

It will be noted that the releasing of a roll is effected without the necessity for inserting the fingers into the recess. The paper is held upon a plain roller without springs and is retained only by the pins 48, 50. The danger of breaking the wooden arbor by the forceful tearing of the cardboard roll therefrom is obviated by the invention. The device therefore greatly simplifies the removal and insertion of rolls of paper.

Although I have shown the device applied to a holder for toilet paper, it will be evident that it is adapted to other environments wherever a strip of material is dispensed from a roll and the

scope of my invention is to be limited only by the scope of the following claims.

I claim as my invention:

1. A dispensing device for rolls comprising a wall receptacle, having a pair of side walls and an end wall, parallel horizontal grooves in said side walls, a paper roll arbor removably inserted in said grooves, and a one-piece, paper roll retaining means seated in said grooves, said retaining means including a roll retaining latch normally disposed in front of the spindle of said paper roll arbor, a handle on said latch and extending outside said receptacle, and means urging said handle and latch into engaging position with said paper roll arbor.

2. A dispensing device for rolls comprising a wall receptacle, having a pair of side walls and an end wall, parallel horizontal grooves in said side walls, a paper roll arbor removably inserted in said grooves, and a one-piece, paper roll retaining means seated in said grooves, said retaining means including a roll retaining latch normally disposed in front of the spindle of said paper roll arbor, spring means carried by said retaining means and abutting an upper wall of said groove.

3. A dispensing device for rolls comprising a wall receptacle, having a pair of side walls and an end wall, parallel horizontal grooves in said side walls, a paper roll arbor removably inserted in said grooves, and a one-piece, paper roll retaining means seated in said grooves, wherein said retaining means comprises a U-shaped unitary member having a leg disposed in each of said grooves and having its bight portion adjacent said end wall.

4. A dispensing device for rolls comprising a wall receptacle, having a pair of side walls and an end wall, parallel horizontal grooves in said side walls, a paper roll arbor removably inserted in said grooves, and a one-piece, paper roll retaining means seated in said grooves, wherein said retaining means comprises a U-shaped unitary member having a leg disposed in each of said grooves and having its bight portion adjacent said end wall, one leg of said retaining means comprising a handle and latch for releasably securing said arbor and paper roll in dispensing position in said grooves.

5. A dispensing device for rolls comprising a wall receptacle, having a pair of side walls and an end wall, parallel horizontal grooves in said side walls, a paper roll arbor removably inserted in said grooves, and a one-piece, paper roll retaining means seated in said grooves, each of said grooves comprising a lower paper roll arbor portion of increased width and an upper, retainer receiving portion of lesser width.
